2 Claims. (Cl. 226—190)

The present invention has for its object a device for the propulsion of wire and thread.

Wire propulsion devices have already been constructed, for example with a view to supplying machines for binding flat coils, wound coils or bundles of rods.

However, the propulsion devices which have been produced up to the present time have never proved fully satisfactory. While the wire is in fact clamped to a sufficient extent to ensure its propulsion at the high speeds which are now commonly achieved, a braking or stoppage of the wire upstream of the propulsion unit results in evolution of heat produced by friction, thereby deforming the wire and causing it to lose its mechanical properties and can even cause it to melt. Furthermore, the starting and stopping operations create similar problems.

The aim of this invention is to overcome the disadvantages referred-to by making available to users a wire propulsion unit which produces a powerful clamping action on the wire but which acts in a progressive manner over a relatively substantial length of wire, with the result that it is thus made possible to operate at high speeds without giving rise to any danger of braking action or stoppage of the wire upstream of the device and without requiring special precautions at the time of starting or stopping of the device.

To this end, a propulsion device in accordance with the invention is essentially characterized in that it comprises two plates mounted side by side on a same shaft, at least one of said plates being mounted on said shaft with play, said plates being driven in rotation and elastically applied one against the other, means being provided for guiding the wire between said two plates over a portion of the periphery of said plates and for withdrawing said plates to a greater distance from each other over an opposite portion of said periphery.

As a preferable feature, one of the plates is keyed on the shaft and drives the other plate, for example by means of studs which are integral with one of the plates and inserted within recesses provided in the other plate.

In a preferred form of embodiment of the invention, the guiding means consist of two half-channels which are formed in the internal faces of the plates and in which the wire can be applied by means of rollers.

In regard to the means for outwardly displacing the plates, said means can be made up of at least one disc and preferably two discs which are interposed between the two plates over a small portion of their peripheries, said discs being freely rotatable on a shaft which is parallel to the plate shaft.

It will be understood that there is thus provided a device whereby the wire is clamped over a relatively substantial portion of the periphery of the two plates, the clamping action being both progressively applied and progressively released.

In fact, inasmuch as the plates are slightly inclined in relation to each other by virtue of the discs which move said plates apart, the distance between said plates in the zone through which the wire passes decreases first very slowly and passes through a minimum then increases again at an equally slow rate, thereby ensuring the clamp-

2

ing of the wire to a sufficient extent and in a progressive manner.

Moreover, the use of two discs makes the system particularly stable since the plate which is not keyed is applied theoretically against the other plate at three points, thus forming an isostatic system.

A clear understanding of the invention will in any case be gained from a perusal of the description which follows below, reference being made to the accompanying drawings which show by way of non-limitative example one form of embodiment of the invention, and in which:

FIG. 1 is a diagrammatic side view of the device;

FIG. 2 is a corresponding sectional view taken along the line II—II of FIG. 1;

FIG. 3 illustrates the device itself, also in cross-section along the line II—II of FIG. 1 but on a larger scale.

It is apparent from FIGS. 1 and 2 that a device according to the invention is essentially composed of two plates 1 and 2, plate 1 being fitted with play by virtue of a bore 3 on a shaft 4 and plate 2 being keyed on said shaft. Three studs 5 which are secured to plate 1 are adapted to work in conjunction with recesses 6 of the plate 2 so that said two plates 1 and 2 can thus be driven by the shaft 4. The plate 1 is also urged against the plate 2 by a spring 7 which is interposed between the head 8 of the shaft 4 and said plate 1, thereby clamping the wire 9 which is applied by means of rollers 10 which are freely rotatable on shafts 11 within a channel formed by two half-channels 12 and 13 which are cut in the peripheries of the internal faces of plates 1 and 2.

FIG. 1 shows that the wire-clamping action referred-to takes place approximately over a sector which is defined by the angle α by virtue of the presence of two discs 14 and 15 which are inserted over a small portion of their peripheries between the plates 1 and 2, said discs being freely rotatable on shafts 16 and 17 which are parallel to the shaft 4 and having a thickness which is chosen so that the two plates 1 and 2 are set closer together in the zone of clamping of the wire 9.

The rolling path of said discs relative to the plates has been chosen so as to be preferably different from the path of the wire 9.

It can be visualized that it is merely necessary to drive the shaft 4 in rotation in the direction of the arrow F in order that the wire is thus driven in the direction of the arrow F₁ by virtue of the clamping action exerted thereon throughout the sector which is defined by the angle α , said clamping action being in addition very progressive since the discs draw together then move apart very slowly.

FIG. 3 shows the method of construction of the device which is illustrated diagrammatically in FIGS. 1 and 2.

There are again shown in this figure the plate 1, the conical bore 3 of which is adapted to accommodate among others the heads of the screws 18 which secure the plate 2 to the bushing 19, said bushing being keyed to the shaft 4 by means of splines and applied by two locking nuts 20 and 21 which are screwed on the shaft against the roller-bearing 22 by virtue of which the shaft rotates within a shell 23. The keying of the plate 2 on the bushing 19 can also be completed by means of keys such as 24.

The studs 5 which are inserted in the recesses 6 are held in position by virtue of their slightly frusto-conical shape and by their screwed heads 25 which are fitted within recesses 26 of the plate 1. Said plate 1 is clamped by a series of frusto-conical flexible washers 7 which are fitted over a shaft end 27, said shaft end being fixed by a threaded bolt 28 which is engaged within an internally threaded bore 29 of the shaft 4. It is the head 8 of the shaft end 27 which clamps the washers 7. The adjustment of the effort exerted is effected by varying the thick-

ness of the washer 7₁; the clamping action can thus be applied by tightening up the bolt 28 which is then locked in position by means of the set-screw 30. The rollers 10 are rotatably mounted on the shafts 11 by means of roller-bearings 31. As shown in the figure, said shafts are mounted in a flared portion of the shell 23 and said flared portion carries a plate 32 which can form between the rollers as well as before and after these latter a wire guide 33 for the wire 9.

Finally, the disc 14 or 15 is carried by roller-bearings 34 which are mounted in conventional manner on the shafts 16 or 17 which are fixed on the flared portion of the shell 23. It will be noted, however, that the sleeve 16₁ is made fast for rotation by means of the locking-plate 16₂ but is freely movable in the axial direction within the shell 23. The rollers 14 and 15 can thus be freely positioned relatively to the plates 1 and 2 and be adapted to any possible wear of these latter.

The operation of the device has already been explained in the foregoing. It need therefore only be added that a certain number of pairs of discs 14 or 15 of increasing thickness can be provided for one device and that each of these pairs can serve for a range of diameters of the wire 9.

It will therefore be apparent that, in addition to the advantages which have been described in the foregoing, the wire propulsion device in accordance with the invention permits the possibility of supplying wires of very different diameters owing to the fact that the two discs 14 and 15 can be changed very rapidly, the changing of discs being in any case effected only if the wire diameter has changed to a considerable extent and being followed if necessary by a change of washer 7₁.

It will further be apparent that detail modifications can be made in the form of embodiment which has just been described without thereby departing either from the scope or the spirit of the invention.

5 What I claim is:

1. Device for the propulsion of wire and thread, comprising two plates mounted side by side on a first shaft, at least one of said plates being mounted on said shaft with play, said plates being driven in rotation and elastically applied one against the other, means being provided for guiding the wire between said two plates over a portion of the periphery of said plates and for withdrawing said plates to a greater distance from each other over an opposite portion of said periphery, the means for outwardly displacing the plates consisting of at least one disc which is interposed between the two plates over a small portion of their peripheries and which is freely rotatable on a second shaft which is parallel to the first shaft.

2. The device in accordance with claim 1, wherein the means for outwardly displacing the plates consist of two discs which are intercalated between the two plates over a small portion of their peripheries and which are freely rotatable on shafts which are parallel to said first shaft.
